(57) **CLAIM**

The ornamental design for a tissue sample receptacle, as shown and described.

DESCRIPTION

FIG. 1 is a front perspective view of a tissue sample receptacle showing our new design.

FIG. 2 is a front side view of the tissue sample receptacle shown in FIG. 1.

FIG. 3 is a back side view of the tissue sample receptacle shown in FIG. 1.

FIG. 4 is a left side view of the tissue sample receptacle shown in FIG. 1.

FIG. 5 is a right side view of the tissue sample receptacle shown in FIG. 1.

FIG. 6 is a top view of the tissue sample receptacle shown in FIG. 1; and,

FIG. 7 is a bottom view of the tissue sample receptacle shown in FIG. 1.

The broken lines show portions of the tissue sample receptacle that form no part of the claimed design.
